AUTOMATIC BLANK FEEDING AND GUMMING MACHINE.

1,282,949.

Specification of Letters Patent. Patented Oct. 29, 1918.

Original application filed June 15, 1917, Serial No. 174,921. Divided and this application filed December 18, 1917. Serial No. 207,684.

To all whom it may concern:

Be it known that we, JAMES D. REIFSNYDER, WILLIAM A. WEIGHTMAN, and ERNEST G. RIDER, citizens of the United States, residing at Weehawken, county of Hudson, State of New Jersey; Logan, Philadelphia, county of Philadelphia, State of Pennsylvania, and Philadelphia, county of Philadelphia, State of Pennsylvania, respectively, have invented new and useful Improvements in Automatic Blank Feeding and Gumming Machines, of which the following is a specification.

This invention relates to machines for gumming wrapper or covering blanks, and more particularly to mechanism for automatically selecting, feeding, gumming and transporting wrapper blanks to mechanisms or instrumentalities for applying the gummed blank to boxes or packages.

The present application is a division of our co-pending application, Ser. No. 174,921 filed June 15, 1917. One of the objects of this invention is to provide a wrapper selecting, feeding, gumming and transporting unit that may be attached to or associated with any box covering or wrapping machine to the end that selected and properly gummed blanks may be fed and delivered to other mechanisms, such as those for applying the blanks to the boxes or packages.

A further object of the invention is the provision of a machine of the character described embodying in its construction a reciprocating carriage having blank gripping devices, said reciprocating carriage being operatively associated with and adapted to remove blanks from gripping devices of rotary glue applying mechanism and feeding such blanks away from the glue applying mechanism and delivering the same to a selected machine such as a box covering or wrapping machine.

Another object of the invention is to provide an automatic blank feeding, gumming and transporting means that may be properly adjusted to permit the feeding, gumming and transporting of wrapper blanks of different sizes.

A still further object of the invention is to provide a novel construction and arrangement of parts that will permit of ready access and adjustment, and this is especially

true of the mechanism for applying the coating of adhesive to the wrapper blanks, the adhesive applying rollers being so mounted that they may be adjusted to vary the thickness of the adhesive coating applied to the blanks and may also be moved to a position where the rollers and glue tank may be easily and quickly removed for cleaning or repair purposes.

Another object of the invention is to provide an improved gumming unit for individual blanks, such unit including a blank-supporting platen and coöperating glue-applying rollers and supply rolls, wherein the said rollers and rolls are mounted upon a bodily movable frame that may be readily moved in directions toward and from the periphery of the platen, whereby to permit easy removal of the rollers and provide for rotation thereof.

With the above recited objects and others of a similar nature in view, our invention consists in the construction, combination and arrangement of parts set forth in and falling within the scope of the appended claims.

In the accompanying drawings:

Figure 1 is a side elevation of the mechanism constructed in accordance with the present invention and showing the same in associated relation with a box-covering machine, the latter being merely conventionally illustrated in dotted outline, as it forms no part of the present invention.

Fig. 2 is a top plan view.

Fig. 3 is a view partly in elevation and partly in vertical section taken longitudinally through the machine.

Fig. 4 is a view partly in elevation and partly in vertical section taken transversely through the wrapper blank adhesive applying means.

Fig. 5 is a detail plan view partly in section of a portion of the glue applying mechanism.

Fig. 6 is a detail plan view partly in section showing the operating mechanism for reciprocating the wrapper transporting carriage and showing also a portion of the mechanism for adjusting the position of the adhesive applying means.

Fig. 7 is a vertical section of a portion of the wrapper blank feeding means shown in association with the adhesive applying roll-

ers and the coöperating blank-supporting platen.

Fig. 8 is a transverse vertical section of a portion of the blank-supporting platen and 5 one of the grippers of the wrapper transporting means, the view illustrating the position of the gripper in the act of taking the adhesively coated wrapper from the platen.

Fig. 9 is a somewhat similar view showing 10 one of the grippers in the act of transporting the adhesively coated wrapper to the box or package wrapping instrumentalities.

Fig. 10 is a transverse sectional view showing 15 a portion of the gripper in the act of gripping the wrapper blank as it passes over the first one of the two glue-applying rollers.

According to the plan of operation of the machine constituting this particular invention the wrapper blanks are arranged in 20 pack form upon a suitable support forming a part of the machine. The wrapper blanks which are to be adhesively coated on one face are fed forward singly from the bottom of the pack over the first one of a pair 25 of glue-applying rollers having spaced glue-applying faces, the glue-applying faces of one roller being opposite the spaces between the faces of the other roller so that the wrapper-blanks when drawn over the two 30 glue-applying rollers will have a coating of adhesive applied over substantially the entire area of one face thereof. A rotary blank supporting platen is coöperatively associated with the two glue-applying rollers, 35 the platen having a gripper or grippers which operate to grasp the forward end of the wrapper blanks as they are successively fed to the rollers, the gripping action taking place just after the forward edge of each 40 wrapper blank has passed over the first one of the two glue-applying rollers, the wrapper blanks receiving the coating of adhesive during rotation of the blank supporting platen.

45 During rotation of the platen with the adhesively coated wrapper blank supported thereon, the grippers of the wrapper transporting device are brought into coöperative association with the forward edge of the 50 blank so that said edge is released from the grippers of the platen and immediately gripped by the grippers of the wrapper transporting device, the latter then operating, for example, to transport the adhesively 55 coated blank bodily to wrapper applying instrumentalities, the wrapper being released when it is properly delivered in registered position, whereupon the wrapper transporting device returns to receive an 60 other wrapper. These operations are carried on automatically and successively to the end that an entirely automatic machine is provided for feeding the wrapper blanks, applying adhesive to a face thereof, and 65 transporting the wrapper blanks in proper

position with relation to other mechanism, such as box covering or wrapping instrumentalities.

The blank feeding, gumming and transporting mechanism is supported upon a 70 supplemental main frame 1^a, which, in the instance shown, may be arranged to one side of and attached in any suitable way to the machine W, here shown conventionally in dotted lines. This supplemental main frame 75 is provided with a pair of spaced apart top plates or rails 1^b each having therethrough longitudinal slots 1^c as more clearly shown in Fig. 2. Upon the said top plates or rails 80 1^b of the supplemental main frame is mounted a longitudinally adjustable carrier frame 1^d, said carrier frame being adjustable toward and from the wrapper applying instrumentalities in order to accommodate blanks of different sizes. Adjustment of the frame is effected by means of screws 14 working in threaded nuts 14^a carried by the frame 1^b, said screws 14 each having a beveled gear 15 at one end, said beveled gears being in mesh with similar 90 beveled gears 16 carried by a shaft 17, the latter being provided at one end with a crank handle 18 by means of which the shaft 17 may be rotated in either direction in order to transmit motion to the screws 14 and thus adjust the carrier frame 1^d toward and from the wrapper applying instrumentalities. When the frame has been brought to proper 95 adjusted position, it may be securely held in such position by means of the screw bolts 19 which pass through the slots 1^c in the top rails 1^b of the supplemental main frame, all as more clearly shown in Fig. 2.

Journaled for rotation in suitable bearings 20, in the upper part of the carrier frame 1^d is a shaft 21, upon which is mounted a blank-supporting platen having the form of a segmental drum 22, which is driven through bevel gears 23, and 24, the latter being mounted upon a vertical shaft 25, having a bevel gear 26 at its lower end all as more clearly shown in Fig. 4. The bevel gear 26, is driven by a similar gear 27, mounted upon the transverse shaft 28, journaled in suitable bearings 29, carried by the 110 carrier frame 1^d and said transverse shaft is driven by bevel gears 30, 31, the latter of which is mounted upon the end of a longitudinal shaft 32. In order to permit of the carrier frame 1^d being adjusted toward and from the wrapper applying mechanism without interfering with the drive gear connections between the transverse shaft 28, and the longitudinal shaft 32, the gear 31 is splined on said shaft 32, as more clearly 115 shown in Fig. 1, where it will be seen that one end of shaft 32 is journaled in a bearing 36, formed as a part of the carrier frame 1^d.

120 Supported for vertical adjustment upon 130

the carrier frame 1^a is an auxiliary frame, the outline of which will be clearly seen in Fig. 1, and other portions of which are shown in Figs. 3 and 4. This auxiliary frame which is made up of the two side frame members or plates 37 and tie-rods 38, is mounted for vertical adjustment in guides 39, Figs. 1, 3, 4 and 5. Adjustment is effected by means of screw rods 40, which pass through threaded nuts 41, each carrying a bevel gear 42, with which mesh other bevel gears 43, carried by a transverse shaft 44, the latter being geared to an operating shaft 45, having a crank handle 46 at one end, all 10 as more clearly shown in Figs. 1 and 3. By manipulating the crank handle 46, it will be apparent that the auxiliary frame may be raised and lowered bodily toward and from the blank-supporting platen 22, for a purpose presently to appear.

It will be seen from the foregoing that the frame part of the blank feeding, gumming and transporting mechanism is made up of three independent frame members, 25 namely the supplemental main frame 1^a, the longitudinally adjustable carrier frame 1^a, and the vertically adjustable auxiliary frame made up of the two side plates 37, the said carrier and auxiliary frames being adjustable 30 relatively to one another at right angles and the two said frames being adjustable bodily or as a unit upon the supplemental main frame 1^a.

The vertically adjustable auxiliary frame 35 supports the automatic wrapper feeding mechanism and the gumming or adhesive applying mechanism, and these parts will now be described in detail, although we do not wish to be understood as binding ourselves to the particular construction shown, as we are aware that changes or additions may be made without departing from the spirit of the invention.

The wrapper blanks which are usually 40 of the "cornered" type are supported in pack form upon an upwardly inclined table 47, and upon tapes 47^a, the table being mounted to reciprocate between guides 48, Fig. 3, toward and from a front stop 49. In 45 advance of the upper end of the table 47, there is mounted an oscillating suction picker roll 50, which operates through a suction aperture or apertures to separate the bottom blank from the pack during each forward 50 reciprocation of the table, the separated blanks being successively projected between a pair of feed rolls 51, 52, located just in advance of the suction roll 50, and being guided toward said feed rolls by means of 55 a finger 53, as more clearly shown in Figs. 3 and 7. The table 47 is reciprocated by means of an oscillating gear segment 54, meshing with a rack 55, upon the underside 60 of the table, said segment being mounted upon an oscillatory shaft 55^a, which is oscil-

lated by means of a strap eccentric 56, mounted upon a shaft 57, journaled in the auxiliary frame. The shaft 57 has a bevel gear 58 at one end, which meshes with a similar gear 59, splined upon a vertical shaft 70 60, the latter carrying a bevel gear 61, at its lower end which meshes with a similar gear 62, splined upon the longitudinal shaft 32, all as more clearly shown in Fig. 1. By reason of the splined connection between the 75 gear 59 and shaft 60, the auxiliary frame may be raised or lowered without interfering with the driving connections.

The feed roll 52, is mounted to move away from its companion feed roll 51, at the moment the suction picker roll 50 advances a blank between the rolls and said roll 52, is then moved up in order to grip the blank between the two feed rolls whereby to feed the blank forward to the gumming mechanism presently to be described. The feed roll 52, is moved in the manner described and in timed relation with the reciprocations of the feed table, by means of a link 63, jointed to an arm 64, secured to the oscillatory shaft 55^a.

Air is exhausted from the suction roll 50, by means of a mechanically operated pump 65, having a flexible tube connection 66, with said roll at any suitable point. The piston 67, of the pump is operated by means of a link 68, jointed to a pivoted lever 69, having a roller at one end that runs in a cam groove 70, formed in the periphery of a drum 71, mounted upon the transverse shaft 28, all 100 as more clearly shown in Figs. 4 and 6. Any suitable form of relief valve may be employed in association with the suction roll 50, to break the suction action in the roll after the latter has operated to separate and initially 105 advance the sheets from the pack. As such valves are old in the art and their operation well understood, it is not necessary to illustrate and describe its action further.

The mechanism employed for applying a 110 surface coating of adhesive to the blanks as they are fed forward from the pack, consists in the instance shown of a pair of spaced parallel glue-applying rollers 72, and 115 73, each comprising a plurality of spaced apart glue-applying faces, the faces of one of the rollers being located opposite the spaces between the faces of the other roller, in such manner that when a blank is drawn over the two rollers it will receive a coating 120 of glue over substantially the entire face thereof. It will be understood, however, that the glue-applying faces may be otherwise arranged so that the blank will receive only stripes or spots of adhesive. Such an arrangement will be so obvious from the disclosure herein that no further reference or illustration is considered necessary.

The glue-applying rollers 72 and 73 as 125 more clearly shown in Figs. 3 and 7 are re- 130

movably journaled at their ends in open bearings 74 each bearing being formed upon the end of a pivoted arm 75, there being two pairs of said arms 75, the arms of each pair crossing each other scissors-like and being pivoted to a shaft 76. The arrangement of the two pairs of arms is such that by a swinging movement thereof toward and from each other, the glue-applying rollers 72 and 73 may be brought toward and from the surface of the blank-supporting platen 22 for a purpose presently to appear. The lower ends of the two pairs of arms 75 are connected by toggle links 77 to a vertically movable rod 78 which rod is normally urged downwardly by a spring 79 coiled about the lower end thereof and one end of which spring bears against an apertured lug 80 through which the rod 78 passes, the lug being formed as a part of the auxiliary frame. Vertical downward movement of the rod 78 may be limited by means of a stop screw 81. For as shown in Fig. 7, this rod 78 is connected to one end of the bell crank arm 83, and the downward movement of the latter is limited by contact with the upper end of this stop screw 81.

One purpose of mounting the glue-applying rollers 72 and 73 upon the swinging arms is to render the rolls capable of being moved toward and from the surface of the blank-supporting platen so that the glue-applying faces of the rolls will not contact with and thus impart glue to the surface of the platen when no blank is fed thereto by the blank-feeding means. Mechanism is provided for automatically rocking the arms on their pivot 76 to simultaneously move the two rolls away from each other and away from the surface of the platen when no sheet is fed and this mechanism, in the instance shown, consists of a bell-crank lever pivoted at 82, the arm 83 of which is linked to the vertically moving rod 78 and the arm 84 of which carries a solenoid magnet 85. The core of the solenoid carries a roller 86 adapted through the solenoid action on its core, to be brought into and out of the path of rotation of a cam 87 mounted upon the shaft 57 as more clearly shown in Fig. 3.

The roller 86 is normally held out of the path of movement of the cam by means of a coil spring 88 as shown in Fig. 4. The solenoid is in circuit with the two blank feed rolls 51 and 52 and the arrangement and operation of parts are such that if the rolls are allowed to contact with one another when no sheet is fed therebetween the circuit will be completed through the solenoid 85 which will cause its armature core to move the roller 86 into the path of movement of the cam 87 so that the cam acting upon the roller 86 will operate to rock the bell crank lever in such a way as to cause the rod 78 to move upwardly and through its toggle

connection with the roller carrying arms 75 to cause the upper ends thereof together with their rollers to move outwardly a sufficient distance to prevent surface contact of the glue-applying faces of the rolls with the peripheral surface of the blank-supporting platen. Whenever a sheet is being properly fed between the feeding rolls 51 and 52 no circuit will be completed to the solenoid 85 and the roller 86 will therefore, by reason of action of the spring 88 be held normally out of the path of rotation of the cam 87 so that the glue-applying faces of the rolls 72 and 73 will be properly positioned to apply a surface coating of glue to a blank supported upon the blank-supporting platen as will presently appear.

The glue-applying rolls 72 and 73 receive a surface coating of glue from a distributor roll 89 located therebelow and in such a position that both of the rolls 72 and 73 rotate in surface contact therewith. The distributor roll 89 receives its glue from a supply roll 90 journaled in slidably adjustable bearings 91 carried by the swinging arms 91^a and receives its glue from a glue tank 92, as will be understood by reference to patent to H. P. Smith, 1,179,672, dated April 18, 1916, wherein such a mechanical arrangement is shown. The glue tank may be of the steam heated type if desired, as more clearly shown in Fig. 3. The tank is removably supported between the two side plates 37 of the auxiliary frame so that it can be readily removed for cleaning purposes. One manner of removably supporting the glue tank is to have it rest at one end upon a cross rod 93 of the auxiliary frame and its other end provided with lugs 94 which rest upon the shaft 82 about which the bell crank lever 84 is pivoted. The slidable bearings in which the distributor roll 90 is mounted may be adjusted so as to increase or decrease the surface contact between the supply roll 90 and the distributor roll 89. This adjustment is effected by means of hand operated screw rods 91^b each of which has a threaded connection with a part of the adjustable bearings 91, as more clearly shown in Figs. 1 and 3.

When it is desired to remove the various rolls of the glue applying mechanism, the auxiliary frame is lowered by the screw mechanism heretofore described whereupon the glue-applying rolls 72 and 73 may be lifted from their open bearings 74 after which the supply roll 90 may be moved outward from the distributor roll 89 by means of the screw rods 91^b. This will permit removal of the supply roll from its bearings after which the glue tank 92 may be bodily removed from its supported position.

The various rolls of the glue-applying mechanism are preferably driven directly from the blank-supporting platen 22 by gearing more clearly shown in Fig. 4, where-

in it will be seen that the blank-supporting platen carries a gear 95 which meshes with gear 96 secured to the shaft of the glue-applying roll 73, said gear 96 being also in mesh with a gear 97 on the shaft of the distributor roll 89. The shaft of the distributor roll 89 is provided with a gear 98 adjacent the gear 97 that meshes with a gear 99 fixed on the shaft of the supply roll 90 by which the latter is driven, all as more clearly shown in Fig. 4. The shaft of the other glue applying roll 72, is provided with a gear 96^a intermeshed with a gear 98^a on the shaft of the distributor roll 89, and from which the said glue applying roll derives its motion.

The feed rolls 51 and 52 are driven from a gear 100 mounted upon the opposite end of the shaft upon which the distributor roll is mounted, said gear 100 meshing with a gear 101 which in turn drives gear 102 on the end of the shaft of the feed roll 51, the feed roll 52 being driven by frictional contact with the roll 51, or if desired, these rolls may be intergeared.

The blank-supporting platen 22 is preferably provided on its surface with a flexible blanket 103, one end of the blanket being securely held by means of a clamp bar 104 adjacent an edge of the cutaway portion of the platen, as more clearly shown in Figs. 7 to 10 inclusive, and the other end of the blanket being wound about a tightener roll 105 journaled in the ends of the platen such roll being provided with a ratchet 106 with which a pawl 107 co-operates to hold the roll 105 against movement when the blanket has been drawn taut about the periphery of the platen. Secured in any suitable manner to the face of the blanket 103 is a raised blank supporting form 108 as more clearly shown in Fig. 2, which form takes the shape of the wrapper blank to which the adhesive coating is to be applied. By providing the raised form the blanks which are supported thereby during the gluing operation are held away from other portions of the surface of the platen not covered by the form, so that no glue can be applied to such other portions of the platen during rotation of the platen when the machine is in operation.

The blank-supporting platen is provided with a plurality of gripper fingers 109 each being longitudinally adjustable upon a shaft 110 extending transversely between the end plates of the platen. These gripper fingers are brought into and out of gripping action with the forward edge of the cutaway portion of the platen by means of a gear segment 112 which meshes with a gear 113 secured to the gripper shaft 110. The gear segment is operated by any suitable means as by a cam groove shown in dotted lines in Fig. 7 to cause the gripper fingers 109 to lie wholly below the surface of the platen as the fingers approach the first glue-apply-

ing roll 72 so that the fingers will not make contact or their free movement be interfered with by said roll. Immediately however the fingers reach a point just beyond the axis of the first glue-applying roll 72, then the segment 112 will be operated to cause the gripper fingers to move to gripping position and thus grip the blank that has been fed thereto by the feed rolls 51 and 52, all as more clearly shown in Fig. 7. The blank being thus initially gripped at a point between the two glue-applying rolls will then be drawn over both of said rolls, the projecting portions of the grippers passing in the spaces between the faces of the second glue-applying roll 73 as shown in Fig. 10, and carried upward and its direction of movement reversed so to speak, so that the forward end of the blank will be moved in the general direction of the wrapper applying instrumentalities indicated at W, with the upper or outer face of the blank coated with adhesive. When that part of the platen which carries the gripper fingers approaches the highest point in its travel as illustrated in Fig. 8, the segment 112 is again operated to lift the gripper fingers slightly. At this moment a blank-end lifting device, which is shown in the form of a plate 114 having a hook or hooks 115 at its upper end and which overlies the surface of the platen and upon which the blank rests, is also moved so as to lift the hooks 115 and the overlying end of the blank away from the surface of the platen to permit the entrance under said lifted end of the blank of a thin stationary gripper member 116 with which a gripper finger 117 co-operates. The plate 114 of which there may be one for each gripper 109 is or are adjustably mounted upon a square bar 118 mounted upon arms 119 secured to a rock shaft 120, the said shaft carrying an arm 121 having a roller 122 at one end thereof which roller is adapted to ride over a suitable cam surface shown in dotted lines in Fig. 7, arranged in the travel path of the roller to cause the blank end lifters to move outward and then inward at proper times to function as described, it being understood that the blank will be gripped between the gripper fingers 109 and the lifters 114, during the lifting movement of the latter and will remain gripped therebetween until the grippers of the blank transporting carriage take hold, as will presently appear.

A yielding strip or strand 109^a is secured at one end to the hub of each gripper finger, its free end projecting freely through an opening in the end of the finger as shown in Fig. 10. The purpose of the strip or strand is to serve as a stop for the forward edge of the blank as it is fed onward by the feed rolls 51 and 52 toward the grippers, thus insuring a perfect register of the blanks

with the edge of the platen, as more clearly shown in Fig. 10. The two members 116 and 117 of the blank transporting grippers are carried by arms 123 attached to and projecting forward from a reciprocating carriage 124 having rollers 125 which travel upon tracks 126. The stationary member 116 of each of the blank transporting grippers is secured to the free end of an arm 123 while the pivoted members 117 are pivoted to said arms. Gripping action may be imparted to the pivoted gripper fingers 117 by any suitable means, such as of rods 127 connected by links 128 to the arms 123. The arms 123 are adjustable laterally toward and from each other upon the carriage 124 by means of bolts and nuts 129, the top plate of the carriage 124 being slotted longitudinally to permit adjustment of the arms as described in order that the grippers 116, 117 may be positioned relative to each other to accommodate blanks of different sizes.

The blank transporting carriage may be reciprocated by any preferred form of mechanism. In the present instance we have shown the carriage as provided with a rack bar 130 with which a reversely operated gear 131 meshes, as more clearly shown in Fig. 1. The reverse gear is driven by intermeshing bevel gears 132 one of which is mounted upon a vertical shaft 133, said shaft having at its lower end a gear 134 meshing with a larger gear 135, such larger gear carrying a pinion 136 meshing with an oscillating rack segment 137 which latter has an arm 138 secured thereto carrying a roller 139 which runs in a cam groove 140 of the drum 71. It will be apparent that rotation of the drum 71 will impart oscillating movements to the segment 137 which, through the driving connections described, will cause the gear 131 to impart reciprocating movements to the rack 130 and therefore to the carriage forming a part of the blank transporting mechanism described.

The pivoted gripper fingers 117 may be lifted away from the fixed finger 116 when these fingers arrive in blank receiving position adjacent the blank supporting platen, by any suitable means. In the instance shown we have provided the arm 128 to which the rod 127 is pivoted with a depending portion 141, the curved lower end of which is adapted to ride upon a fixed inclined face 142 properly positioned so that the fingers will open when they reach the blank receiving position, as more clearly shown in Fig. 1, and will close immediately the carriage starts to move forward and will thus grip the blank while it is still on the platen and transport it forward as hereinbefore described. When the carriage with its blank reaches the depositing position the grippers 116, 117 will again be separated to

release the blank, this separation being effected by the part 141 again coming into contact with an adjustably mounted cam 142^a as shown in dotted lines.

We have provided means for imparting an initial advancing movement to the wrapper-blank transporting carriage and its grippers, directly from the blank-supporting platen during rotation thereof, in order to provide for accuracy and uniformity in the gripping action of the grippers upon the blanks as they are delivered by the platen to thereby insure a more perfect register of the blanks at the point of delivery. Claims as to this feature of the invention are included in our co-pending application, Serial No. 174,921, hereinbefore referred to.

One manner of accomplishing this is more clearly shown in Figs. 8 and 9 of the drawings, where it will be seen that the gripper member 116 of the wrapper transporting carriage is provided with a downwardly extending pin or projection 116^a which is arranged to be engaged by an edge of the cut-away portion of the blank-supporting platen when the latter reaches the position shown in Fig. 8. In reaching this position the grippers 116 and 117 of the blank-supporting carriage are supposed to be in the position shown in said figure wherein the grippers are just grasping the forward edge of the blank which is still on the platen.

The platen continuing to move engages the pin or projection 116^a and imparts an initial forward movement thereto operating to initially advance the carriage. Such initial movement is possible because there is necessarily more or less lost motion in the gearing and other connections heretofore described for imparting the back and forth movements to the carriage. By giving the initial advance movement to the carriage through the medium of the blank-supporting platen itself, the adhesively coated wrapper-blanks are always gripped at the same point because the projection 116^a insures this.

It will be seen by referring to Fig. 3 that the table for supporting the pack of blanks is located at a point between the glue-applying mechanism and the conventionally illustrated wrapper applying instrumentalities and that the arrangement is such that as the blanks are fed successively from the table to the glue applying mechanism, they will be directed reversely by the blank supporting platen which rotates in the direction of the arrow, Fig. 3, so that after having a surface coating of glue applied thereto the blanks will be carried in the general direction of the wrapper applying instrumentalities with the adhesively coated face arranged uppermost. This arrangement of the various parts we consider to be an important feature of the invention since it does not re-

quire any additional means for inverting or reversing the wrapper blank after it has received its surface coating of adhesive.

The operation of the machine herein shown and described is as follows, reference being made to the wrapping instrumentalities simply for a better understanding.

A pack of wrapper blanks is first placed upon the blank supporting table of the 10 wrapper feeding means and the machine is then set in operation.

The individual blanks of the pack are selected by the automatic feeding means and fed forward successively between the feed 15 rolls 51 and 52 which in turn feed the blanks between the bight of the first one of the pair of glue-applying rollers and the periphery of the blank-supporting platen. Immediately one of the gripper fingers 109 reaches 20 a point just beyond the glue-applying faces of the first glue-applying roller, said finger swings outward and over into gripping engagement with the forward edge of the blank and during the continued rotation of 25 the platen the blank is drawn over both of the glue-applying rollers, the gripper fingers being so arranged as to pass through the spaces separating the faces of the second glue-applying roller. Continued onward 30 movement of the platen carries the blank in the general direction of the box or package covering instrumentalities, the blank receiving a surface coating of adhesive as it is drawn over the two glue-applying rollers 35 72 and 73.

When the gripper fingers of the platen reach the highest point in their movement, or just prior to reaching such point they move upward and at about the same time 40 the blank end lifting device or devices also move upward to lift the forward end of the blank away from the platen as shown in Fig. 8. In the meantime the fixed member 116 of the blank transporting grippers will 45 have been moved to a position under the lifted end of the blank whereupon the pivoted finger 117 will be caused to grip the blank, and the gripper finger 109 at the same time releasing its hold on the blank. 50 The blank transporting device then carries the adhesively coated blank over to and deposits it at the wrapper applying instrumentalities. The gripper fingers of the blank transporting device release the blank 55 at the proper moment and the carriage is then moved back to receive a fresh blank, which, during the operations last described, has had a coating of glue applied thereto and brought to position to be gripped by 60 the transporting device. These operations are carried on successively and automatically.

While we have herein shown and described a preferred embodiment of our invention, we do not wish to be understood

as limiting ourselves to this particular form of construction, as variation and modification may be made without departing from the spirit of the invention or exceeding the scope of the appended claims.

70

What we claim is:

1. A blank feeding and gumming mechanism of the class described comprising a pair of glue-applying rollers each having a plurality of spaced glue-applying faces, 75 said rollers being so arranged relative to each other that the glue-applying faces of one roller lie opposite the spaces between the faces of the other roller, a blank supporting platen coöperating with the glue- 80 applying faces of both said rollers for pressing the blank thereagainst, and a gripper carried by and movable with the platen operating to grasp a blank adjacent one of the glue-applying rollers and draw it over 85 the said rollers, whereby glue is applied over substantially the entire face of the blank by the successive action of both rollers during the movement of the blank thereover.

90

2. In a machine for gumming sheets, a pair of glue applying rollers each having spaced glue applying faces arranged to successively apply glue to one face of sheets fed thereover, a rotary sheet supporting 95 platen coöperatively associated with said glue applying rollers, means for feeding sheets singly between a peripheral portion of the platen and the first one of said pair of glue applying rollers, grippers mounted 100 upon and movable with the platen, means for actuating said grippers to cause them to grip each sheet after the advance end thereof has passed over the first one of said glue applying rollers and for drawing the 105 sheets over the other glue applying roller, and a reciprocating carriage having grippers movable toward and from the platen for transferring the glued sheets to a point of delivery.

110

3. In a machine for gumming sheets, a plurality of pairs of pivoted cross arms, each pair having a scissors-like movement and each arm having a bearing at one end to provide supports for the journals of glue 115 applying rollers, a pair of spaced glue applying rollers having journals movably supported in the bearings of said cross arms and arranged to apply glue to one face of sheets fed thereover, means for feeding the sheets singly to and over the glue applying rollers, a rotary sheet supporting platen coöperatively associated with the glue applying rollers and grippers carried by and movable with the platen for engaging the sheets 120 and for drawing them over the glue applying rollers.

125

4. In a machine for gumming sheets, a plurality of pairs of pivoted cross arms each pair having a scissors-like movement, said 130

arms constituting supports for glue applying rollers, a pair of glue-applying rollers supported on said arms and arranged to apply glue to one face of sheets fed thereover, means for feeding sheets singly to the glue applying rollers, a rotary sheet supporting platen co-operatively associated with the glue applying rollers, grippers movable with the platen for engaging the sheets and for drawing them over the glue applying rollers, and means connected with the said pivoted cross arms for automatically operating said arms to move the rollers toward and from the periphery of the platen at predetermined times.

5. In a machine for gumming sheets, spaced frame members each having vertically extending guides, a rotary sheet-supporting platen journaled for rotation in said frame members, an auxiliary frame located between the said spaced frame members and having guides complementary to the first named guides, glue applying mechanism carried by the auxiliary frame and including glue applying rollers arranged to contact with the periphery of the said platen, bearings in which said rollers are removably mounted, and means for raising the auxiliary frame bodily to bring the rollers in cooperative association with the periphery of the platen and for lowering the frame away from the platen to permit ready removal of the glue applying rollers.

6. In a machine for gumming sheets, a frame, a rotary sheet supporting platen mounted for rotation thereupon, glue applying mechanism including removably supported glue applying rollers co-operatively associated with the periphery of the platen, and an auxiliary frame movable bodily vertically upon the first named frame in directions toward and from the periphery of the platen and upon which the gumming mechanism is mounted and means for moving the said auxiliary frame away from the platen to permit removal of the glue applying rollers.

7. In a machine for gumming sheets, a main frame, a longitudinally adjustable carrier frame, a wrapper supporting platen journaled for rotation in said frame, an auxiliary frame mounted for vertical adjustment upon the carrier frame, wrapper feeding means and gumming means mounted upon the auxiliary frame, means for bodily adjusting the auxiliary frame vertically toward and from the platen, and a reciprocating wrapper transporting device co-operatively associated with the platen for taking the wrappers therefrom successively and transporting them to a point of delivery.

8. Blank feeding, gumming and transporting mechanism for operating upon individual blanks, comprising a pair of glue-applying rollers, each having spaced glue-

applying faces, said rollers being so arranged relative to each other that the glue-applying faces of one roller lie opposite the spaces between the faces of the other roller, a traveling blank supporting platen co-operating with the glue-applying rollers for pressing the blank thereagainst, means for selecting and feeding the blanks singly between the glue-applying rollers and platen, grippers mounted upon and movable with the platen operating to grasp an edge of a blank after it has passed over one of the glue-applying rollers and draw it over the other glue-applying roller, and a reciprocating gripper for transporting the adhesively coated blanks from the platen to a point of delivery.

9. In a machine for feeding, gumming and transporting individual blanks, spaced glue-applying rollers each having spaced glue-applying faces arranged to apply glue to one face of a blank drawn thereover, means for supporting a pack of blanks and for feeding them singly to and over said glue-applying rollers, a rotary blank-supporting platen having its lower peripheral portion co-operatively associated with both the said glue-applying rollers, grippers mounted upon said platen for gripping an edge of each blank after it has passed over one of the glue-applying rollers and for drawing the blank over the other glue-applying roller, and a reciprocating carriage having grippers for taking the blanks from the platen and delivering them successively at a predetermined point, said pack supporting and feeding means being located beneath the path of movement of the reciprocating carriage.

10. In a machine of the class described and in combination, a machine frame, a blank supporting platen rotatably mounted thereon, glue-applying rollers co-operatively associated with said platen for applying glue to a blank supported thereon, pivoted cross-arms having a scissors-like movement, in which said rollers are journaled, a glue tank, rolls for applying glue from the tank to the glue-applying rollers, means for selecting and feeding sheets singly between said glue-applying rollers and platen, and automatic means operable upon the failure of a sheet to be delivered between the platen and glue-applying rollers for swinging said cross-arms to move the rollers out of contact with the surface of the platen.

11. Blank feeding, gumming and transporting mechanism including a rotary blank-supporting platen, a pair of spaced glue-applying rollers co-operatively associated therewith, each roller having spaced glue-applying faces adapted to contact with a blank supported upon the periphery of the platen, means for feeding blanks between the said rollers and platen pivoted

cross-arms in which the glue-applying rollers are mounted, said arms having a scissors-like movement, and a blank transporting device coöperatively associated with the 5 platen for taking the adhesively coated blanks therefrom and transporting them to a point of delivery.

12. Blank feeding, gumming and transporting mechanism including a rotatable 10 blank-supporting segment having grippers thereon, a pair of glue-applying rollers coöperatively associated with the said segment, each roller having spaced glue-applying faces, means for feeding blanks between 15 one of said rollers and the segment, means

for causing the grippers to grip an edge of each blank after it has passed over the first one of said pair of glue-applying rollers and for drawing the blank over the second glue-applying roller, swinging arms having 20 scissors-like movements in which the glue-applying rollers are mounted, and mechanical means for swinging the arms to move the rollers into and out of contact with the face of the segment.

In testimony whereof we have hereunto set our hands.

JAMES D. REIFSNYDER,
WILLIAM A. WEIGHTMAN.
ERNEST G. RIDER.
